UNITED STATES PATENT OFFICE.

JOHANNES CRONING, OF HAMBURG, GERMANY.

CYLINDER LOCK.

Application filed January 11, 1923. Serial No. 612,062.

To all whom it may concern:

Be it known that I, JOHANNES CRONING, a citizen of the Republic of Germany, residing at Hamburg, Germany, have invented 5 certain new and useful Improvements in Cylinder Locks; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 The present invention relates to improvements in cylinder locks of the pin tumbler type, and more particularly refers to the cylinder plug of such locks.

The object of this invention is to provide 20 improved means for reliably protecting the cylinder plug from axial displacement in said cylinder.

With this end in view the invention consists in certain novel features of construction and combinations of parts as will be hereinafter fully described and pointed out 25 in the claims with reference to the accompanying sheet of drawings in which:

Figure 1 is a vertical longitudinal section 30 of the cylinder lock showing the cylinder in section and the plug inserted therein in elevation; Fig. 2 is a plan in section of Fig. 1 and Fig. 3 is an end view of the rear face of the plug; Fig. 4 is an end view of 35 the annular stop plate for securing the plug within the cylinder against axial displacement; Figs. 5 and 6 are views analogous to Fig. 3 illustrating the mode of applying the said stop plate to the plug; and Fig. 7 is 40 a fragmentary vertical longitudinal section of Fig. 6.

Similar letters of reference designate like parts throughout the several figures.

The plug *a* rotatably mounted within the 45 stationary cylinder *b* rests or bears with a collar or flange *c* against a suitable shoulder of the front end of the said cylinder. The annular plate *d* suitably fixed in a circumferential groove *e* of the plug *a* bears against 50 a corresponding shoulder of the inner or rear end of the cylinder. The flange *c* and the annular plate *d* actually form stops which hold the plug in the cylinder *b* in such a manner that the said plug may be 55 rotated therein but can not move in longitudinal direction. The plug is provided in

its outer circumferential wall with two oppositely situated recesses *f* and *g* serving for the transmission of the rotation of the plug to the locking mechanism. Furthermore the plug has on its top a dovetailed groove *h* in which is located a bolt or bar *i* forming a support for the locking springs not shown. A fourth groove *h* provided in the plug forms the key slot. The circular 60 groove *e* of the plug is interrupted or crossed by the said four longitudinal recesses or grooves (Fig. 3). The annular stop plate *d* (Fig. 4) the inside diameter of which is equal to the outside diameter of 65 the plug, has four inner projections or shoulders *f*¹ *g*¹ *h*¹ and *k*¹ directed toward the centre of the annular stop plate *d* that fit into the corresponding recesses and 70 grooves of the plug, (Fig. 5). Preferably 75 at diametrically opposite places there are fastened to the outside circumference of the annular plate *d* rectangular lugs *l* and *m* (Fig. 7) which serve for applying an implement when inserting the said plate. After 80 the plate *d* has been placed upon the plug *a* to register with the groove *e* (Fig. 5), the said plate *d* is turned in the direction of the arrows until the lug *m* registers with the groove *h* (Fig. 6). In this position the 85 projections *f*¹ *g*¹ *h*¹ and *k*¹ have engaged in the manner of a bayonet-coupling the corresponding full parts of the rear face of the plug *a*. If now the lug *m* is bent 90 down from the position shown in dotted lines into the position shown in full lines (Fig. 7), so as to engage the rear part of the groove *h*, the said plate *d* on the one hand is secured against rotation on the plug and on the other hand prevents the bar *i* from 95 axial displacement in its groove *h*.

In cylinder locks of well known construction the plug is secured against axial displacement by means of a separate disk or plate screwed onto the rear end face of the cylinder. This construction has the disadvantage that shocks and the like imparted to the lock may loosen the fixing screws of the said disk whereby the reliable function of the lock may be risked. This disadvantage is obviated by the present invention according to which the plug is secured in place and prevented from getting loose and from being axially displaced by means of the improved annular stop plate fastened upon the 100 rear end of the plug in the manner of a bayonet coupling and adapted to rest or bear 105

against the rear end of the cylinder. Besides this advantage the use of the improved bayonet coupling for rotatably connecting the plug to the cylinder will simplify and 5 cheapen the whole construction of the lock. The annular groove in the plug can easily be made by means of the turning-lathe, the separate fixing screws are thus dispensed with also the drilling and countersinking of the 10 screw holes as well as the cutting of the internal screw threads therein. This is a very important feature, as tapping-drills break very easily wherefrom results, as known, a great waste of tool and material.

15 I claim:

1. A cylinder lock of the kind described having a stationary cylinder and a rotatable flanged plug held in position therein, an annular stop plate securing said plug against 20 axial displacement and a bayonet connection between the plate and plug.
2. A cylinder lock of the kind described having in combination a stationary hollow

cylinder, a rotative flanged plug, a circumferential groove and a plurality of longitudinal grooves thereon, the latter traversing the former, an annular stop plate fitting on the plug, projections on the inner wall of the said annular stop plate, the said projections being adapted to slide in the longitudinal 25 grooves and to fit in the circumferential groove of the plug, and means for securing the annular stop plate in the circumferential groove.

3. A cylinder lock of the kind described, 30 having in combination a stationary hollow cylinder, a rotatable flanged plug therein, an annular stop plate, means on the plug and on the annular stop plate, adapted to form a bayonet coupling, and means adapted 40 to secure the annular stop plate against rotation on the plug.

In testimony that I claim the foregoing as my invention, I have signed my name.

JOHANNES CRONING.
